UNITED STATES PATENT OFFICE.

JOHN E. FITZGERALD, OF PROVIDENCE, RHODE ISLAND.

FINGER-RING.

SPECIFICATION forming part of Letters Patent No. 766,435, dated August 2, 1904.

Application filed June 7, 1904. Serial No. 211,530. (No model.)

To all whom it may concern:

Be it known that I, JOHN E. FITZGERALD, a citizen of the United States, residing at Providence, in the county of Providence and State of Rhode Island, have invented a new and useful Improvement in Finger-Rings, of which the following is a specification.

This invention has reference to an improvement in finger-rings, and more particularly to an improvement in the means for detachably securing a plate having a letter, emblem, or jewel on its face to the head of the ring.

The object of my invention is to improve the construction of a finger-ring having means for detachably securing a plate to the head of the ring, said plate forming the face of the head and may be plain or ornamented with a letter of the alphabet, monogram, emblem, or it may form the setting for a jewel, if desired.

My invention consists in the peculiar and novel construction of a finger-ring having a hollow box-shaped head, an aperture in the bottom of the head, a flat spring-tongue having its free end over the aperture and its fixed end secured to the bottom of the head, a ledge on the inner side wall of the head, a plate adapted to fit in the head and rest on the ledge, a finger on the under side of the plate shaped to go under the ledge, a yoke on the under side of the plate adapted to receive the free end of the spring-tongue, and other details of construction, as will be more fully set forth hereinafter.

Figure 1 is a side view of my improved finger-ring. Fig. 2 is a face view of the ring, showing the detachable face-plate on which is a letter of the alphabet. Fig. 3 is an enlarged face view of the ring with the face-plate removed, showing the spring-tongue for securing the plate to the ring. Fig. 4 is an underneath view of the face-plate removed from the ring. Fig. 5 is a side edge view of the face-plate, showing the finger for securing one end of the plate to the ring. Fig. 6 is an end edge view of the face-plate, showing the yoke through which the free end of the spring-tongue passes for securing the other end of the plate to the ring; and Fig. 7 is a sectional view taken lengthwise through the head, showing the face-plate secured in the ring-head in full

lines and in the position for removal or insertion with the tool for doing the same in broken lines.

In the drawings, *a* indicates the ring, *b* the face-plate, and *c* the tool for removing the plate. (Shown in broken lines in Fig. 7.) The ring *a* has the oval box-head *a'*, in the bottom of which adjacent one end is the aperture *a''* and on the inner side wall of the head the ledge *a''*, cut out to form the opening *a''*. The flat spring-tongue *a''* lies lengthwise on the bottom of the box-head *a'* in a position to bring its free end *a''* over the aperture *a''* and has its fixed end *a''*, in which is the hole *a''*, secured to the bottom of the head *a'* by soldering the strap *a''* to the bottom of the head over the tongue and forcing a portion of the strap into the hole *a''* in the tongue, as shown in Figs. 3 and 7.

The face-plate *b* has on its face a letter of the alphabet, as shown in Fig. 2. On the under side of the face-plate *b* is the finger *b'*, shaped to catch under the ledge *a''* over the fixed end of the spring-tongue *a''*, and the yoke *b''*, having the opening *b''* to receive the free end *a''* of the spring-tongue *a''* and the stud *b''*, adapted to enter and fill the aperture *a''* in the bottom of the head *a'* flush with the interior surface of the ring. The tool *c* (shown in broken lines in Fig. 7) is shaped to enter the hole *a''* in the bottom of the head *a'* and force the face-plate upward by pushing on the stud *b''*.

By the use of my improved finger-ring a dealer in the trade may carry a small number of rings and a large assortment of face-plates having letters, emblems, monograms, or jewels. After fitting the buyer with the size of ring required a different face-plate is usually wanted. A tool *c* (shown in broken lines in Fig. 7) is now used to force the face-plate outward by pushing the stud *b''* out of the hole *a''*. This raises the free end of the spring-tongue *a''* and the face-plate *b* into the position as shown in broken lines in Fig. 7, when the plate may be easily removed by sliding the free end *a''* of the spring-tongue out of the hole *b''* in the yoke *b''*, the opening *a''* in the ledge *a''* materially assisting this movement. The new plate is now inserted by sliding the

free end of the spring-tongue into the hole b^3 in the yoke b^2 and the finger b' under the ledge a^3 on the head a' and removing the tool c from the aperture a^2 . The plate is now firmly held 5 in the head on the ledge a^3 by the finger b' under the ledge and the tension of the spring-tongue a^5 on the yoke b^2 , as shown in full lines in Fig. 7, and cannot be removed except by a tool adapted to force up the stud b^4 10 through the aperture a^2 in the ring against the tension of the spring-tongue.

Having thus described my invention, I claim as new and desire to secure by Letters Patent—

1. In a finger-ring, means for detachably 15 securing a face-plate to the head of the ring, consisting of a spring-tongue secured at one end to the bottom of the head, an internal ledge on the side wall of the head, a finger on the under side of the face-plate adapted to 20 catch on the ledge, and a yoke on the under side of the face-plate adapted to receive the free end of the spring-tongue, as described.

2. A finger-ring having a box-head in the bottom of which is an aperture, a ledge on the 25 inner side wall of the head, a spring-tongue

secured at one end to the bottom of the head, a plate shaped to fit the head and rest on the ledge, a finger on the under side of the plate adapted to catch under the ledge, a yoke on the under side of the plate having an opening 30 to receive the free end of the spring-tongue, and a stud on the yoke adapted to enter the aperture in the bottom of the head, as described.

3. In a finger-ring the combination of a ring 35 a having the box-head a' in the bottom of which is the aperture a^2 and on the side wall the ledge a^3 cut out to form the opening a^4 , a spring-tongue a^5 having the free end a^6 and the fixed end a^7 secured to the bottom of the 40 head by the strap a^8 , and a plate b having the finger b' and the yoke b^2 forming the opening b^3 and the stud b^4 , as described.

In testimony whereof I have signed my name to this specification in the presence of two sub- 45 scribing witnesses.

JOHN E. FITZGERALD.
